UNITED STATES PATENT OFFICE.

CHARLES EDWARD HAVILAND, OF LIMOGES, FRANCE.

DESIGN FOR A COVERED DISH.

SPECIFICATION forming part of Design No. 24,168, dated April 2, 1895.

Application filed December 13, 1894. Serial No. 531,728. Term of patent 7 years.

To all whom it may concern:

Be it known that I, CHARLES EDWARD HAVILAND, a citizen of the United States, residing at the city of Limoges, in the Republic of France, have invented and produced a new and original Design for a Covered Dish, of which the following is a specification, reference being had to the accompanying drawings, forming part thereof, in which—

10 Figure 1 is a top view of a covered dish, bearing my design. Fig. 2 is a side elevation of same; and Fig. 3 is a detached sectional view through a portion of same on the dotted line 3—3 of Fig. 1.

15 The leading feature of my design consists in the new and original shape and configuration of the said covered dish, as shown in the drawings forming a part of this application.

In the drawings A designates the body of 20 the dish and B the cover therefor. The cover B has a raised central portion and thence inclines on graceful lines to the outer edge of said cover, along which edge are the scallops C, D, the scallops D being smaller than and 25 intermediate the scallops C. Upon the top of the cover B is a suitable handle E.

The body A of the dish projects outward along its middle portion and thence tapers up-

ward to the upper edge of the said body and downward to the base F, and the said body 30 A along its sides is composed of the scalloped sections G, H, corresponding with the scalloped sections C, D, along the edge of the cover B, the sections of the body A and cover B thus corresponding with each other. Upon 35 opposite ends of the body A are suitable handles I.

The shape and configuration of the covered dish made the subject hereof are clearly illustrated in the drawings forming a part of this 40 application and from which drawings the arrangement and form of the scalloped sections of the body A and cover B, and of the top of the cover B and sides of the body A may be clearly observed. 45

What I claim is—

The design for a covered dish, substantially as shown and described.

Signed at the city of Limoges, in the Republic of France, this 23d day of November, 50 A. D. 1894.

CHARLES EDWARD HAVILAND.
